COMBINATION SHUTTER AWNING

Edmund Jerome Burke, West Palm Beach, Fla.

Application January 5, 1939, Serial No. 249,382

7 Claims. (Cl. 20—59)

This invention relates to a combination awning and shutter.

More particularly the invention relates to a device which may be used selectively either as an awning or as a shutter to cover a window opening without the need for removing the awning and substituting shutters, or vice versa.

The simplicity of the device renders the construction relatively inexpensive to make, even though it is ornamental in appearance.

Another feature of the invention relates to the simplicity of construction wherein a minimum number of parts is used.

Another feature of the invention relates to the construction whereby when the device is used as a shutter covering an entire window opening it may be locked in closed position.

Other objects and advantages of this invention will appear from the following specification and 20 claims, and it will be apparent in the accompanying drawings in which—

Fig. 1 is a view in elevation showing the device used as a shutter;

Fig. 2 is an enlarged vertical sectional view 25 taken substantially on the line 2—2 of Fig. 1;

Fig. 3 is a view in vertical cross-section similar to Fig. 2, showing the parts in the raised position as used as an awning; and

Fig. 4 is an enlarged view showing certain 30 details of and the relation between adjacent slats of the device and their manner of mounting on their spring supporting element.

Referring in detail to the drawings, in Fig. 1 is shown a partial wall structure 10 of a house 35 or other building having window frames 12 defining window openings therein. The window frames and openings may be of substantially standard condition having upper and lower window sashes 14 and 15 respectively (Fig. 2).

As viewed in Fig. 1, the full length of the window opening is closed by the device which 40 incorporates the features of the present invention and comprises a plurality of slats 16 secured to and mounted on spiral coil springs 18 and 20, these, therefore, constituting elastically extensible elements. These springs, which are alike, are arranged to be secured at their respective upper ends 22 and 24 to the window frame structure as shown by hooking the ends 45 of the springs over hooks 23 and 25 (Fig. 4), and they are secured at their lower ends 28 and 30 to a stretcher rod 34. As shown in Fig. 1, the rod 34 is U-shaped and has two side arms 36 and 38 adjustably, that is pivotally, secured 50 to a portion 12a of the window frame at 40 and

42 respectively. The stretcher rod 34 has a portion intermediate the arms 36 and 38 which extends transversely of the window opening and to which the spring elements are secured as just indicated.

The stretcher rod 34 is provided with a securing element 44 which may be a rope, chain or other element secured to the rod at an intermediate point 46 between the side arms and arranged to pass through an aperture 48 in a sill 50 of the window frame. A similar aperture 52 is arranged on the inner wall member of the window frame so that the rope 44 may extend therethrough for adjustment of the combination shutter and awning. As shown in Fig. 2, 15 the location of the opening 48 is such as not to interfere with the movement of the window sash.

When the device is used as a shutter, as seen in Figs. 1 and 2, the rope 44 is drawn tight and 20 fastened about a hook 54 as seen in Fig. 2, thereby serving as a locking element for the shutter. In this position, the springs 18 and 20, being extensible elements, are stretched. It will be noted that they serve as the sole support for 25 the cross slats.

As illustrated in Fig. 4, each of the slats 16 is arranged to be mounted on the spring elements, of which 20 is one, by means of suitable fastening means 56 which have loops 60 en- 30 circling or enclosing one turn of the coil spring 20 and the two free end portions of the fastening means 56 are secured to one end edge portion of the slats by appropriate means such as screws 58.

It may be desirable in certain constructions to also attach resilient spring members 62 adjacent the edge of each slat opposite to the fastening means 56 so that the springs may rest upon the next adjacent slat and serve as a spacing means to allow for circulation of air and the entrance of light.

As illustrated in Fig. 3, the entire weight of the slats 16, stretcher rod 34 and arms 36 and 38 is supported by the springs 20, the springs 45 sagging somewhat under the weight of the slats to provide the curve substantially shown in Fig. 3. The movable slats overlap to the extent of about 50% of their width, and in that position the springs 18 and 20 are not under tension, 50 whereas when the device is used as a shutter as observed in Fig. 2, and is extended to close the full length of the window opening, the turns of the coil springs have been pulled apart and the slats have been moved relatively with re- 55

spect to each other and overlap each other less than when used as an awning as shown in Fig. 3. Thus, while using a substantially standard construction, the device is readily adapted to 5 different dimensioned window openings.

Further referring to Fig. 3, it will be noted that in the side view, as illustrated, the weight of the slats causes the structure to assume a slight curve or concavity facing upwardly, which 10 enhances the ornamental appearance of simplicity of the structure.

It will be apparent from this description and from the drawings that the springs 18 and 20 comprise supporting means, the length of each of 15 which is adjustable from the retracted condition shown in Fig. 3 to the extended shape shown in Figs. 2 and 4, and furthermore, that all portions along a given length of these members are adjustable to the same degree. In other words, 20 when the springs 18 and 20 are tensioned by elongating the structure for use as a shutter, the springs being of uniform size throughout their length, the adjacent turns open up or separate the same distance throughout the length 25 of the spring. In this way, a substantially equal movement of the slats relative to each other is assured.

I claim:

1. In a combined awning and shutter, a stretcher rod adapted to extend transversely of a window frame and having two arms adapted to be 30 adjustably secured to the opposite sides of a window frame, a plurality of relatively movable slats extending parallel to said rod and in overlapping relation to each other, a plurality of extensible spring members connected to the top of a window frame and to said rod, and means for securing each slat to said springs.

2. In a combined awning and shutter, a substantially rigid stretcher member adapted to extend transversely of a window frame and having 40 two arms adapted to be adjustably secured to the opposite sides of a window frame, a plurality of relatively movable slats extending parallel to said stretcher member and in 45 overlapping relation to each other, a plurality of extensible spring members connected to the top of a window frame and to said stretcher member, means for securing each slat to said 50 springs, and means for locking the device in position as a shutter and substantially in the plane of the window frame enclosing the window opening, the said springs being contracted and adjacent slats overlapping each other to the greatest extent when the device is in the open and 55 raised position and said arms extend outwardly from the window frame, and said springs being extended and adjacent slats overlapping each other to the minimum extent possible in their assembled relation when the device is used in the 60 plane of the window frame and said arms extend substantially parallel to the window and said stretcher member is in its lowermost position.

3. In a combined awning and shutter, a 65 stretcher rod adapted to extend transversely of a window frame and having two arms adapted to be adjustably secured to the opposite sides of a window frame, a plurality of relatively movable slats extending parallel to said rod and in 70 overlapping relation to each other, a plurality of extensible spring members connected to the top of a window frame and to said rod, means for

securing each slat to said springs, and means resiliently spacing adjacent slats from each other.

4. In a combined awning and shutter, a substantially rigid stretcher member adapted to extend transversely of a window frame and having 5 two arms adapted to be adjustably secured to the opposite sides of a window frame, a plurality of relatively movable slats extending parallel to said stretcher member and in 10 overlapping relation to each other, a plurality of extensible spring members connected to the top of a window frame and to said stretcher member, means for securing each slat to said springs, means for locking the device in position as a 15 shutter and substantially in the plane of the window frame enclosing the window opening, and means resiliently spacing adjacent slats from each other, the said springs being contracted and adjacent slats overlapping each other to the greatest extent when the device is in the open and 20 raised position and said arms extend outwardly from the window frame, and said springs being extended and adjacent slats overlapping each other to the minimum extent possible in their assembled relation when the device is used in the 25 plane of the window frame and said arms extend substantially parallel to the window and said stretcher member is in its lowermost position.

5. In a combined awning and shutter, a 30 stretcher rod adjustably secured to a window frame at the opposite sides thereof and extending transversely of the width of the window, a plurality of relatively movable slats extending parallel to said rod, a plurality of spring members secured to the window frame and to said 35 rod, means mounting each of said slats on said spring members, and means for holding the device in the fully extended position when used as a shutter and substantially in the plane of the window frame, said means for mounting the 40 slats comprising a series of connecting elements each secured to the spring at one point along its length and each connecting element having another portion of which is secured to the slat, there being one such connecting element for each 45 slat opposite each spring member.

6. In an awning device, a rod adapted to extend substantially the width of the window frame, a plurality of coiled springs of substantially equal size throughout the length thereof having 50 their upper ends secured to the frame at the upper side of the window opening and their lower ends secured to said rod, and a plurality of relatively movable slats extending parallel to said rod arranged in overlapping parallel relation and mounted on and supported solely by said springs.

7. In an awning device, a rod adapted to extend substantially the width of the window frame, a plurality of coiled springs of substantially equal 60 size throughout the length thereof having their upper ends secured to the frame at the upper side of the window opening and their lower ends secured to said rod, a plurality of relatively movable slats extending parallel to said rod arranged 65 in overlapping parallel relation and mounted on and supported solely by said springs, and means for spacing that portion of said rod to which said springs are secured away from the window frame in certain positions.
